RECUPERATIVE COUNTER-FLOW FURNACE

Edwin L. Smalley, Whitefish Bay, Wis., assignor
to Hevi Duty Electric Company, Milwaukee,
Wis., a Corporation of Wisconsin

Original application June 5, 1929, Serial No.
368,646. Divided and this application July 10,
1930. Serial No. 467,077

10 Claims. (Cl. 263—6)

My invention relates broadly to furnaces and more particularly to a furnace of the recuperative counter-flow type.

This application is a division of my application Serial No. 368,646, filed June 5, 1929, for recuperative counter-flow furnace.

One of the objects of my invention is to provide a construction of recuperative counter-flow furnace in which minimum floor area is necessary for the installation of the furnace for the heat treatment of materials.

Another object of my invention is to provide a furnace structure in which the temperature of the articles or material to be heat treated may be uniformly raised by a preheating process, the article or material then subjected to a uniform heat treatment temperature and thereafter the articles or material reduced in temperature at a uniform rate.

Still another object of my invention is to provide a construction of heat treatment furnace with parts arranged to control the direction of convection heat currents for the preheating, heat treatment and temperature reducing processes to which the material or articles being passed through the furnace may be subjected.

A further object of my invention is to provide a construction of recuperative counter-flow furnace in which means are provided for moving articles through the furnace, with automatic means at one end of the furnace for imparting moving forces to the moving system by which the articles are carried, and means at the other end of the furnace for removing articles therefrom to allow the entry of articles to be subjected to heat treatment.

A still further object of my invention is to provide a construction of recuperative counter-flow furnace having means for shifting material subjected to heat treatment from one chamber to another for the horizontal movement of the material through the chambers during the course of preheating, heat treatment and cooling processes.

Another object of my invention is to provide a combined system of heat treatment and cooling chambers in a recuperative counter-flow furnace system with means for controlling the passage of material through the chambers operating to mechanically shift material from one chamber to another during the process of heat treatment.

Still another object of my invention is to provide a combined system of heat treatment and cooling chambers in a furnace where special

means are provided for distributing the cooling currents which circulate through the cooling chambers, in directions where the convection currents may be controlled to effect maximum cooling while maintaining temperature uniformity of the successive parts of the charges as they move through the cooling chambers.

A further object of my invention is to provide a mechanical system for loading a pre-heating chamber of the recuperative counter-flow furnace at one end while removing a charge in timed relation thereto at the opposite end of the furnace.

Other and further objects of my invention reside in the construction of a recuperative counter-flow furnace, as will be more fully pointed out in the specification hereinafter following by reference to the accompanying drawings, in which:

Figure 1 is a longitudinal cross-sectional view taken centrally through a combined preheating, heat treatment and cooling chamber arrangement in a recuperative counter-flow furnace having construction embodying the principles of my invention; Fig. 2 is a cross-sectional view through the cooling and preheating chamber construction of the furnace illustrated on line 2—2 of Fig. 1; Fig. 3 is a cross-sectional view taken on line 3—3 of Fig. 1 showing the arrangement of the heat treatment chambers in the horizontal type of recuperative counter-flow furnace; Fig. 4 is a longitudinal cross-sectional view taken through the horizontal type of recuperative counter-flow furnace on line 4—4 of Fig. 2; Fig. 5 is a plan view of the floor plate in the cooling and preheating chambers of the recuperative counter-flow furnace construction illustrated in Figs. 1—4; and Fig. 6 is a diagrammatic view explaining one manner of moving charges through the furnace.

Referring to the drawings in detail, the furnace system of my invention comprises a multiplicity of chambers disposed adjacent each other, one of the chambers comprising a pre-heating chamber, the next succeeding pair of chambers having heat treatment means therein, and the final chamber comprising a cooling chamber.

Referring to the drawings, the furnace system of my invention has been illustrated wherein the preheating, heat treatment and cooling chambers are located in horizontal alignment adjacent each other as shown in Figs. 1—4. The heat treatment chambers are shown side by side at 47 and 48, one preheating chamber 49a being

adjacent to one cooling chamber 50, and another preheating chamber 49 being adjacent to another cooling chamber 50a, and all with a central longitudinal division wall 80 between. All chambers are enclosed by suitable walls 51 having arched construction. On the interior of heat treatment chambers 47 and 48, I mount heating elements 8 in a manner similar to the arrangement of heating elements in the furnace of my Letters Patent 1,768,865 dated July 1, 1930, although any method of heating may be employed. The walls of the furnace 51 are of suitable fire brick and heat insulating material and a furnace shell is provided enclosing the furnace walls. Pushing mechanisms may be used for progressing the charges through the furnace on trays 19. The cooling chambers are connected with adjacent preheating chambers by flues 54 which receive convection currents through ports 52 of the cooling chambers 50 and 50a and conduct such convection currents through ports 53 in the arches of preheating chambers 49 and 49a, where the charges on trays 19 in preheating chambers are preheated. Trays 19 preferably have a perforated bottom through which convection gases as indicated by arrows in Fig. 2 may readily pass. This is especially desirable when the tray supports a charge through which convection gases may readily flow. The convection of air currents is downward through the ports 55 of ceramic or metallic refractory plates 56 forming the support for rails 17, then along horizontal flues 57 and upwardly through the ports or openings 55 in plates 56 in the cooling chambers 50 and 50a. The ports 55 in the plate 56, as shown more clearly in Fig. 5, are graduated, with the largest openings farthest from the cooling charge, to control the direction of flow of the air or gases. The convection currents, shown by arrows in Fig. 2, are guided by ports 52, flue 54, ports 53, ports 55 and flue 57, in such manner as to fully distribute the cooling influence of the air on the charges in the cooling chambers 50 and 50a while preheating the charges introduced in preheating chambers 49 and 49a. The paths of movements in reverse direction of the two charges passing through the furnace have been shown by arrows 59 and 59a, where each charge is gradually progressed through a preheating chamber to the heat treatment chamber, and then through a cooling chamber.

In Fig. 6 I have shown a method of loading the furnace where a suitable form of reciprocatory pusher apparatus is indicated at 60 for shifting a loaded tray 19 into the preheating chamber. As the tray passes from cooling chamber it is disposed upon a suitable platform or conveyor 61 and may be removed therefrom by any suitable means. It will be understood that a similar reciprocatory pusher mechanism may be employed in directing loaded trays in their course of movement in the opposite direction through the adjacent duplex chamber system in the furnace structure of my invention.

While I have described my invention in one of its preferred embodiments I desire that it be understood that modifications may be made and that no limitations upon my invention are intended other than are imposed by the scope of the appended claims.

What I claim as new and desire to secure by Letters Patent of the United States is as follows:

1. In a furnace, a plurality of chambers comprising preheating, heating and cooling cham-

bers disposed in horizontal rows adjacent each other, the chambers in each row being aligned end to end for the passage of material to be heat treated therethrough, the preheating chamber of one row being directly adjacent the cooling chamber of another row, the heating chamber of one row being directly adjacent the heating chamber of another row and the cooling chamber of the first mentioned row being immediately adjacent the preheating chamber of the second mentioned row, bottom plates closing each of said preheating and cooling chambers and apertured for the uniform distribution of convection currents therebetween, the upper portion of said preheating and cooling chambers being connected by flues one with the other, and flues interconnecting said chambers below said bottom plates for uniformly directing the circulation of convection currents through said chambers and through the flues interconnecting said chambers.

2. In a furnace, a multiplicity of chambers comprising preheating, heating and cooling chambers aligned in horizontal rows disposed one adjacent the other with a division wall therebetween, plate members forming the supporting bottoms for each of said preheating and cooling chambers, each of said plate members being provided with apertures varying in size from a relatively small cross-section adjacent the division wall to larger cross-sections remote from said division wall for the distribution of convection currents therethrough, the upper portions of said preheating and cooling chambers being apertured for providing a path for the circulation of convection currents, and flues in the upper and lower portions of said preheating and cooling chambers for directing convection currents therebetween through the apertured upper portions and said apertured bottom plate members of the preheating and cooling chambers.

3. In a furnace, a refractory housing, a division wall extending longitudinally thereof, a multiplicity of chambers aligned end to end in a horizontal plane on each side of said division wall comprising preheating, heating and cooling chambers, bottom plates extending across said preheating and cooling chambers, said plates being apertured for the passage of convection currents therethrough, the upper portions of said preheating and cooling chambers being apertured for the circulation of convection currents, flues interconnecting the lower portions of said preheating and cooling chambers beneath said apertured plates, flues connecting the upper portions of said preheating and cooling chambers above the apertures therein, the apertures in said plates and the apertures in the upper portion of each of said last mentioned chambers graduating in size from a minimum adjacent the wall dividing said last mentioned chambers to a maximum adjacent the walls of the refractory housing for distributing the convection currents through said preheating and cooling chambers uniformly throughout the area thereof.

4. In a furnace, a pair of rows of longitudinally aligned chambers, a wall dividing said chambers into cooperatively related adjacent sections, the intermediate sections constituting heat treatment chambers, the sections on one end thereof constituting preheating chambers and cooling chambers respectively, and the sections on the opposite ends thereof constituting cooling and preheating chambers respectively.

- lateral flues interconnecting one of said cooling chambers with the adjacent one of said pre-heating chambers, and ports between said flues and said preheating and cooling chambers, said 5 ports varying in cross-section from a minimum size adjacent the wall intermediate said pre-heating and cooling chambers to a maximum adjacent the remote sides of said chambers for controlling the temperature conditions therein.
- 10 5. In a furnace, a multiplicity of rows of longitudinally aligned chambers disposed side by side, a wall dividing said chambers into a plurality of adjacent sections, the intermediate section in each row constituting a heat treatment chamber 15 and the sections on either end thereof constituting preheating and cooling chambers respectively, the order of chambers in one row being reversed with respect to the order of the chambers in the adjacent row, flues interconnecting 20 the preheating and cooling chambers at one end of said rows and separate flues interconnecting the cooling and preheating chambers at the opposite end of said rows, and ports disposed between said flues and said preheating and cooling 25 chambers, said ports increasing in cross-section from a minimum adjacent the wall dividing said preheating and cooling chambers to a maximum adjacent the outer walls of said chambers for graduating the temperature conditions therein.
- 30 6. In a furnace, a duplex system of chambers, a wall dividing said system of chambers into a plurality of sections disposed end to end, the intermediate section of each system comprising a heat treatment chamber and the sections on 35 each end thereof constituting cooling and pre-heating chambers respectively, supporting plates extending across the bottom of each of said cooling and preheating chambers, ports in said plates, and flues beneath said plates interconnecting adjacent cooling and preheating chambers, said ports increasing in cross-section from a minimum adjacent the wall between said preheating and cooling chambers to a maximum adjacent the outer walls of said chambers.
- 40 7. In a furnace, a duplex system of chambers, a wall dividing said system of chambers into a plurality of sections disposed end to end, the intermediate sections constituting heat treatment chambers and the sections on opposite ends thereof constituting preheating and cooling chambers respectively, the preheating and cooling chambers in said duplex system of chambers being disposed laterally side by side, flues interconnecting the upper and lower portions of said 45 preheating and cooling chambers, ports disposed between the ends of said flues and said preheating and cooling chambers, said ports varying in cross-section from a minimum size adjacent the wall dividing said preheating and cooling chambers to a maximum adjacent the remote sides of said chambers for graduating the temperature conditions therein.
- 50 8. In a furnace, a duplex system of chambers disposed in horizontally extending rows with a division wall therebetween said chambers being divided into a plurality of sections, the inter-
- mediate sections constituting heat treatment chambers and the end sections constituting pre-heating and cooling chambers respectively, with the preheating chamber in one row directly adjacent the cooling chamber of the adjacent row, flues interconnecting the top of the preheating chamber in one row with the top of the cooling chamber in the adjacent row, supporting plates extending across the bottom of said preheating and cooling chambers and ports in said plates, said ports increasing in cross-section from a minimum adjacent the division wall between said preheating and cooling chambers to a maximum adjacent the outer walls of said chambers for the circulation of convection currents between said preheating and cooling chambers during the course of movement of articles under heat treatment through said chambers in opposite directions.
- 55 9. In a recuperative counterflow furnace, a multiplicity of aligned chambers disposed longitudinally end to end and laterally side by side, a longitudinally extending wall dividing said chambers into a multiplicity of sections, the intermediate sections constituting heat treatment 60 chambers and the adjacent end sections constituting preheating and cooling chambers respectively, transverse flues interconnecting the top of adjacent preheating and cooling chambers at one end of said furnace, independent sets of 65 transverse flues interconnecting the top of the cooling and preheating chambers at the opposite end of said furnace, supporting plates extending across the bottom of said preheating and cooling chambers, flues beneath said plates intercon- 70 necting the adjacent preheating and cooling chambers and ports in the tops of said preheating and cooling chambers and in said plates, said ports being graduated in size from a minimum adjacent the wall between said preheating and cooling chambers to a maximum adjacent the remote walls of said chambers for the distribution of convection currents through the preheating and cooling chambers for the simultaneous 75 heating of charges entering one heat treatment chamber and the simultaneous cooling of charges leaving the adjacent heat chamber.
- 80 10. In a recuperative counter-flow furnace, a plurality of chambers disposed in rows adjacent each other, the chambers in one row comprising a preheating chamber, a heat treatment chamber and a cooling chamber arranged in the order named and the chambers in the adjacent row comprising a cooling chamber, a heat treatment chamber and a preheating chamber ar- 85 ranged in the order named, laterally disposed flues interconnecting said cooling and preheating chambers, and a plurality of ports disposed between the ends of said flues and said preheating and cooling chambers, said ports gradu- 90 ating in size from a relatively narrow width adjacent said preheating and cooling chambers to a greater width remote from said preheating and cooling chambers.

EDWIN L. SMALLEY. 143
